INVENTOR
Arthur J. Miehle,
By J. Daniel Stuve
ATTORNEY.

UNITED STATES PATENT OFFICE.

ARTHUR J. MIEHLE, OF CHICAGO, ILLINOIS.

PIPE WRENCH.

Application filed September 6, 1927. Serial No. 217,560.

My invention relates to a pipe wrench; and an object of the invention is to provide such a wrench which can be readily adjusted to its closed operative position and to its open 5 inoperative position, and which can be entirely opened instantly by the use of only one hand. Another object is to provide such a wrench which will be self-locking when the jaws are moved to the closed operative position, and wherein such lock will be automatically released by moving the jaws to their open inoperative position.

Other objects and advantages will become apparent from the following description, 15 taken in connection with the accompanying drawing, in which

Fig. 1 is a view showing the preferred form of my wrench, in an intermediate open position;

Fig. 2 is a slightly enlarged view thereof, in an open or inoperative position, with the side plate of the housing removed;

Fig. 3 is a similar view, but showing the parts in their closed or operative position; 25 and

Fig. 4 is a vertical cross-section, taken on line 4—4 of Fig. 3.

The form of construction of my improved wrench which I prefer, and which is illustrated in the drawing, comprises a jaw member 10 including a handle portion 11 at one end and a serrated head or jaw 12 at the opposite end; and further comprises a jaw member 13 including a short operating finger or lug 14 at one end and a serrated bent-over portion or jaw 15 at the opposite end, said member 13 being slidable relative to its companion member 10, and jaw 15 being swingable relative to its companion jaw 12, to move into operative and into inoperative position.

The means for connecting the jaw members 10 and 13 comprises a frame or housing which includes similar side plates 16 connected together in spaced relation by transverse posts 17, 17', and 17'', the jaw member 13 being pivotally or swingably supported on the upper post 17, and the jaw member 10 having slidable relation with the housing and the other jaw member by reason of its location between lower posts 17'' and intermediate posts 17'.

Means is provided for holding and locking the wrench in closed or operative position, 55 and this means preferably comprises a hold-

ing lever or member 20 fulcrumed on one of the posts 17' and provided with indentations or teeth 21 which engage in similar indentations or teeth 22 formed at the side of jaw member 10. Said means further comprises locking members or levers 23, fulcrumed on one of the posts 17'', and carrying a locking pin or cross pin 24 which is arranged and positioned to move in a notch 25 provided on lever 20, to permit movement to release position of the latter, as indicated in Fig. 2 of the drawing; and said pin engages and bears on the outer end 20' of said lever 20, beyond notch 25, to retain or lock said lever in its operative position, as indicated in Fig. 3 of the drawing. This locking means becomes operative when jaw member 13 is swung to its operative or closed position.

I also provide means for positively and automatically releasing said locking means when jaw member 13 is swung back to its release or inoperative position, and this means comprises releasing members 27, preferably in the form of plates fastened on jaw member 13, as with a pin 28, and having each a finger 29 arranged to engage a locking lever 23 and move locking pin 24 back from end 20' of lever 20 into the notch 25, as lug 14 is depressed and jaw 15 is moved upward from pipe 30. This releasing means further includes a pair 35 of actuating or lifting members 31, pivoted with a pin 32 on holding lever 20, and having each a hook or bent end 33 for engaging in a notch 34 in releasing member 27, so as to actuate lever 20 into or out of engagement with jaw member 10.

I furthermore provide spring means 35 tending to urge the parts into their operative or closed position and to retain them therein, and this means preferably includes a bowed leaf spring which is mounted with its ends in cuts or slots provided in members 23 and 31, a spring being preferably placed at each side of member 10, for each set of members 23 and 31. This spring means or pair of 100 springs is so mounted in said slots in members 23 and 31, and is so constructed, that it is stressed when the jaw members are swung apart, and will thus urge them toward their closed position or to swing jaw 15 down into 105 alinement with jaw member 10.

To operate my improved wrench:

When it is desired to open and adjust the wrench for a pipe or article, the lug 14 can be depressed with the thumb of the hand 110

which holds the handle 11, swinging jaw member 13 sufficiently to have the releasing fingers 29 thereon move locking levers 23 over so that locking pin 24 slides from end 20' of lever 20 into notch 25, and in the mean time hooks 33 of levers 31 have been engaged and moved upward by the notched parts 34 of plates 27 thereby lifting said levers 31 and consequently the pivotally attached holding lever 20 until its teeth 21 have released teeth 22 on jaw member 10, whereupon the jaw member 13 with the housing and the contained operating elements are readily slid or moved lengthwise of jaw member 10, to the desired position for gripping the pipe, whereupon the jaws will automatically close upon the pipe, by the operation or working of the wrench, as shown in Fig. 3, with the elements or parts returned to their closed or operative positions, assisted by the action of springs 35. To release the wrench, the lug 14 is again depressed by the thumb sufficiently to separate teeth 21 and 22, so that member 13 with the housing may be slid along member 10. Said teeth are tapered to facilitate the separating and sliding movement.

The construction furthermore is so arranged that when it is desired to quickly open the wrench to the full extent, it is merely necessary to grasp the handle 11 with one hand and thrust or swing the wrench forward or downward, said wrench being normally held closed by spring 35, as seen in Fig. 3; whereupon, as the handle 11 is brought suddenly to rest by the stopping hand, the jaw 15 continues and swings upward and outward from jaw 12, and moves the member 13 substantially parallel with member 10 and sufficiently to separate teeth 21 and 22, as seen in Fig. 1, and thereupon sliding member 13 with the housing and contained elements along jaw member 10 to the jaw 12 at its end, thus with one thrust of one hand fully opening the wrench, all ready for applying it to a large size pipe or article.

The pipe wrench of this application is an improvement over the form of construction disclosed in the patent issued to W. S. Miehle, March 8, 1910, #951,570, wherein the hooked-lever 11 was used to move arm 15 of bell-crank 14 for actuating the locking means, which was not always effective; nor was that wrench adapted to be fully opened by merely thrusting or swinging it, by the use of only one hand, like this wrench.

What I claim as my invention and desire to secure by Letters Patent is:

1. A pipe wrench comprising a member including a jaw and a handle, a cooperating jaw member mounted to swing and to move longitudinally with respect to the first said member, means to normally retain said members in operative position, and means to positively release said retaining means, all parts being arranged to enable positive releasing

and complete opening of said jaw members by grasping said handle and thrusting and suddenly stopping said wrench.

2. A pipe wrench comprising a jaw member including a handle, a jaw member which is swingable and movable longitudinally with respect to the first said jaw member, means for holding said members in their operative position, means for locking said holding means, and means on said swingable member for releasing the locking means from the holding means by the swinging of said member, thereby enabling the sliding of said swingable jaw member along the other jaw member to the full open position automatically by a sudden jerking and stopping movement of the wrench.

3. A pipe wrench comprising a jaw member having a handle, a housing slidable on said member, a jaw member pivotally mounted in said housing and having a short lug extending beyond the housing, means for holding said jaw members in position, means for locking said holding means, and a finger on said pivoted jaw member for engaging and releasing said locking means to open the jaw members by depressing said lug.

4. A pipe wrench comprising a jaw member, a housing slidable thereon, a jaw member having a thumb lug at one end and being pivotally mounted in said housing adjacent said lug, means in said housing for holding said housing and pivoted member against sliding movement on the other member, means for locking said holding means, means including a finger on said pivoted member for releasing said locking means and thereupon releasing said holding means by depressing said lug, and spring means for normally urging said parts into operative locking position.

5. A pipe wrench comprising a main jaw member, a housing slidable thereon, a jaw member swingably mounted in said housing, means for holding said housing stationary on said main member, means for locking said holding means, means for lifting said holding means to release said main member, and means fixed on said swingable member, including a finger to positively push said locking means to release position also a notched portion to lift said lifting means and thereby release said holding means from said main member.

6. A pipe wrench comprising a jaw member with a handle, a housing slidable thereon, a jaw member pivotally mounted in the housing, means for holding said housing stationary, a lever with means for locking said holding means, a lever for lifting and releasing said holding means, means on said pivoted jaw member with a finger for releasing said locking means and with a notched portion for lifting said lifting lever to release said holding means, and a bowed spring which has its ends seated in slots in said locking lever and

in said lifting lever for moving the parts of the wrench to the operative locking position.

7. A pipe wrench comprising a main jaw member having a handle and side teeth, a housing slidable along said member, a jaw member having a lug at its end and being pivoted in said housing adjacent said lug, holding means pivoted in the housing and having teeth for engaging the teeth on the main member, also having a notch near its free end, locking levers with a cross-pin therebetween to bear on said free end and hold said means locked, a pair of hooked levers on the holding means for lifting it to separate the teeth, releasing members fixed on the pivoted jaw

members and having integral fingers for pressing the locking levers to move their cross-pin from said free end to said notch, said releasing members being notched for actuating the hooks and lifting levers, and bowed springs with their ends seated deep in slots in said lifting levers and locking levers to move the various parts of the wrench to the operative locking position, said wrench being fully openable by a jerking and sudden stopping movement thereof with one hand. 20 25

In testimony whereof I have signed my name to this specification.

ARTHUR J. MIEHLE.
